signors to General Mills, Inc., a corporation of
Delaware

Application June 12, 1948, Serial No. 146,933

Term of patent 14 years

(Cl. D81—10)

To all whom it may concern:

Be it known that we, John N. Polivka, George T. Scharfenberg, and Vernoid M. Butterfield, citizens of the United States, residing at Minneapolis, in the county of Hennepin and State of Minnesota, have invented a new, original, and ornamental Design for a Toaster Casing Section, of which the following is a specification, reference being had to the accompanying drawing, forming part thereof.

In the drawing:

Figure 1 is a side elevation of a toaster casing section embodying our new design;

Fig. 2 is a top plan view of the casing section of Fig. 1; and

Fig. 3 is an end elevation of the same.

We claim:

The ornamental design for a toaster casing section, as shown.

JOHN N. POLIVKA.

GEORGE T. SCHARFENBERG.

VERNOID M. BUTTERFIELD.
